UNITED STATES PATENT OFFICE.

LORENZO B. HORNER, OF HAMMOND, INDIANA.

RAIL-SPlice.

1,320,231.

Specification of Letters Patent.

Patented Oct. 28, 1919.

Application filed June 6, 1919. Serial No. 302,153.

To all whom it may concern:

Be it known that I, LORENZO B. HORNER, a citizen of the United States, residing at Hammond, in the county of Lake and State 5 of Indiana, have invented new and useful Improvements in Rail-Splices, of which the following is a specification.

This invention comprehends a rail joint which affords the rail maximum strength 10 at this point; eliminates the well known clicking sound as the wheels pass over the joint, the rail sections being identical in construction whereby they can be turned end for end to facilitate laying of a continuous 15 rail.

The nature and advantages of the invention will be readily apparent when the following detailed description is taken in connection with the accompanying drawing, 20 the invention residing in the construction, and arrangement of parts as claimed.

In the drawing forming part of this specification, like numerals of reference indicate similar parts in the several views, and 25 wherein:—

Figure 1 is a plan view partly in section of the adjacent ends of the rail sections joined.

Fig. 2 is a detail view of one of the rail 30 sections.

Fig. 3 is a similar view of one of the fish plates.

Fig. 4 is a transverse sectional view taken on line 4—4 of Fig. 1.

35 In carrying out my invention each rail section is constructed in the manner illustrated in Fig. 1, wherein the rail proper indicated at A has its intermediate portion 10 of uniform cross sectional configuration,

while the opposite ends of the sections are 40 cut on one side as at 11 diagonally from an appropriate point in its length and in a vertical plane. One of these cut ends terminates substantially flush with the corresponding end of the base 12, while the other 45 of said cut ends of the section projects beyond its adjacent end of the rail as clearly shown. When the rail sections are laid end to end in the formation of a continuous rail the straight edges of the bases of the re- 50 spective sections are arranged in face to face contact, while the end portion of one section projecting beyond the base thereof reposes upon the base of the adjacent section. When the sections are thus joined, a joint of 55 maximum strength is produced, eliminating all projections and the usual clicking sound when the wheels pass over the joint. The rail sections when associated, can be secured together by any suitable fastening means, such 60 as indicated at 14. Each section being identical in construction at its opposite ends, permits the sections to be turned end for end to facilitate the laying of a continuous rail.

What I claim is:—

65 A rail section comprising an intermediate portion of uniform dimension and cross sectional configuration, the opposite ends of said section being each cut at one side diagonally in a vertical plane, a base of uniform 70 width, one of the said cutaway end portions projecting beyond the corresponding end of the base and adapted to repose upon the base of the adjoining section while the cutaway end portion of the adjoining rail 75 section is coextensive with the base.

In testimony whereof I affix my signature.

LORENZO B. HORNER.
